Primary Examiner — Ania Aman*(74) Attorney, Agent, or Firm* — Fred Zollinger(57) **CLAIM**

The ornamental design for a fire pit, as shown and described.

DESCRIPTION

FIG. 1 is an upper perspective view of a first embodiment of a fire pit showing my new design.

FIG. 2 is top plan view thereof.

FIG. 3 is an upper perspective view of a second embodiment of a fire pit showing my new design; and,

FIG. 4 is top plan view thereof.

The dashed lines shown in the drawings are for purposes of illustrating portions of the article that form no part of the claimed design.
